COMBINED PACKAGING TRAY AND COVER

Karl Rune Persson, Halmstad, Sweden, assignor to Duni
Bila AB, Halmstad, Sweden

Filed Mar. 6, 1974, Ser. No. 448,696

Claims priority, application Sweden Sept. 10, 1973

Term of patent 14 years

Int. Cl. D9—03

U.S. Cl. D9—219

FIG. 1.

FIG. 2.

FIG. 3.

FIG. 4.

FIG. 5.

FIG. 6.FIG. 1 is a top perspective view of a combined packaging tray and cover, showing my new design;

FIG. 2 is a bottom perspective thereof;

FIG. 3 is a top perspective view thereof with the cover omitted;

FIG. 4 is a bottom perspective view showing a modified form of my new design wherein the tray is more shallow;

FIG. 5 is a top perspective view thereof with the cover omitted; and

FIG. 6 is a perspective of the cover used with either tray.

I claim:

The ornamental design for a combined packaging tray and cover, as shown and described.
